US0D1050180S

(12) **United States Design Patent** (10) **Patent No.:** **US D1,050,180 S**
(45) **Date of Patent:** **** Nov. 5, 2024**

(54) **DISPLAY SCREEN OR PORTION THEREOF WITH AN ICON**

(71) Applicant: **DEERE & COMPANY**, Moline, IL (US)

(72) Inventors: **Carolyn R. Herman**, La Porte City, IA (US); **Hanna J. Wickman**, Grimes, IA (US); **Nathanael K. Rehn**, Waterloo, IA (US); **Zachary Shaver**, Cedar Falls, IA (US)

(73) Assignee: **DEERE & COMPANY**, Moline, IL (US)

(**) Term: **15 Years**

(21) Appl. No.: **29/884,372**

(22) Filed: **Feb. 10, 2023**

(51) LOC (14) Cl. **14-04**

(52) U.S. Cl.

USPC **D14/489**

CLAIM

The ornamental design for a display screen or portion thereof with an icon, as shown and described.

DESCRIPTION

FIG. 1 is a front view of a display screen or portion thereof with an icon according to a first embodiment of our new design; and,

FIG. 2 is a front view of a display screen or portion thereof with an icon according to a second embodiment of our new design.

The outermost long-dash short-dash broken line illustrates a display screen or portion thereof with an icon and forms no part of the claimed design.

1 Claim, 1 Drawing Sheet
